Primary Examiner—Nelson C. Holtje*Assistant Examiner*—Martie Thompson*Attorney, Agent, or Firm*—Koch, Robert J.[57]*CLAIM

The ornamental design for a combined pen, chain and wall-mountable bracket therefor, as shown and described.

DESCRIPTION

FIG. 1 is a perspective view of a combined pen, chain and wall-mountable bracket therefor showing my new design with the pen shown separated;

FIG. 2 is a perspective view with the pen in a stored position;

FIG. 3 is a top plan view;

FIG. 4 is a bottom plan view;

FIG. 5 is a front elevational view with the bracket removed for convenience of illustration;

FIG. 6 is a front elevational view of FIG. 5 with the pen shown separated;

FIG. 7 is a side elevational view of FIG. 6;

FIG. 8 is a rear elevational view of FIG. 2;

FIG. 9 is a side elevational view of FIG. 1;

FIG. 10 is a front perspective view of FIG. 5;

FIG. 11 is a front perspective view of FIG. 6; and,

FIG. 12 is a perspective view of FIG. 1 in an exploded condition.
